UNITED STATES PATENT OFFICE.

SHINKICHI TAMURA, OF KOBE, AND MASANORI WATANABE, OF TOKYO, JAPAN; SAID WATANABE ASSIGNOR TO SAID TAMURA.

APPARATUS FOR CHANGE SPEED OF MOTOR-CARS.

1,348,251.

Specification of Letters Patent.

Patented Aug. 3, 1920.

Application filed August 1, 1918. Serial No. 247,884.

To all whom it may concern:

Be it known that we, SHINKICHI TAMURA and MASANORI WATANABE, subjects of the Emperor of Japan, and the former residing at No. 11 Nakayamate-Dori Gochome, Kobe, Japan, and the latter at No. 39 Takecho, Shitaya, Tokyo, Japan, have invented certain new and useful Improvements in Apparatus for Change Speed of Motor-Cars, of which the following is a specification.

The invention comprehends generally improvements in that class of inventions known as machine elements and more particularly relates to a variable speed gearing especially adapted to motor cars.

The object of the invention is to provide an apparatus of the above mentioned character, the construction of which is comparatively simple, and permits of the changing of the speed of the car more easily than such action is accomplished by other types of variable speed gearing.

Briefly the invention may be said to consist of several sets of planetary gears, for instance, for high, low and reverse speeds, mounted on drums, which with the gears are compactly arranged in a single oil containing casing, the parts being arranged so that the different speed gearing normally mesh with the driving or motor shaft and the driven shaft, but only transmit motion from one shaft to the other when one of the selectively controlled drums is clutched or held against rotation. In addition there is provided a brake at the outside of the casing and this brake as well as the gears are controlled in operation by a single lever mechanism operating in conjunction with a single sliding arm. The arrangement of the parts is such that, not only the different speed gearing may be operated at will, but also, when the brake is operated, any gear transmitting motion is automatically separated from either the driving or driven shafts to stop such transmission motion.

One form of the invention is clearly illustrated in the accompanying drawings, in which:—

Figure 1 is a sectional view taken on line 1—1 of Fig. 2.

Fig. 2 is a sectional view taken on the line 2—2 in Fig. 1 and looking in the direction in which the arrow points.

Fig. 3 is an end elevation, partly in sec-

tion, the latter being taken on the line 3—3 in Fig. 1.

Fig. 4 is a side elevational detail of a part of the improved apparatus, and

Fig. 5 is a plan view of the same.

Similar characters of reference are employed in all of the above described views to indicate corresponding parts.

Referring now more particularly to the drawings there is provided a motor or driving shaft 1 preferably rotated by the motor of the cars through suitable gearing (not shown). A second shaft 2 is provided through the speed changing apparatus according to this invention and transmits the power of the motor to the axle of the rear wheels of the car through a bevel gear or other suitable gearing, (not shown). The projecting end of the shaft 1 enters into a recessed portion at the end of the shaft 2 and is supported by ball bearings 3 to facilitate the relative rotation. The drums A, B and C are employed and in each is arranged a set of planetary gears. The center pinion 5 in the drum A is fixed to the shaft 1 and planet gears 6, which are geared with the pinion 5, are fixed to shafts 7 journaled in bearings of the same drum A. The planet gears or wheels 8, fixed upon the said shafts 7, are geared with the central pinion 9, which is fixed to the shaft 2. The drum A, after receiving these members, is closed by a cover A' which is fixed thereto by means of bolts A'' while the boss of the drum is loose on the shaft 1. In the drum B, the planet gears 10, fixed to the common shafts 7, are geared with a center pinion 11 which is fixed to the boss of the drum B. The boss of this drum B is loose on the shaft 2. In the drum C, the planet gears 12 fixed to the common shafts 7 are geared with a center gear 13 which is fixed to the boss of the said drum C. The boss of this drum, like in the cases of the other bosses, is loose on the shaft 1. In the example shown, three sets of planetary gears are provided for one center wheel, but as apparent, they may be varied in number at will.

Encircling the outside of each drum A, B and C are band brakes 14, 15 and 16 respectively. The tension of these bands may be easily adjusted as will be hereinafter more fully described. By adjusting a sliding arm

23, the sliding piece 21 bears against one of the operating rods 14', 15' or 16', thereby tightening the brake band to stop the rotation of the drum. When the sliding arm 23 is brought midway between the operating rods, none of the bands operate. Therefore, if the sliding piece 21 is brought to bear upon the rod 14' to cause the brake band 14 to stop the drum A, the shaft 7 will be fixed 5 and accordingly planet gears 6 and 8 will rotate without revolving around the center pinion 9. As a result the rotation of the shaft 1 is transmitted to the shaft 2 by a certain reduced ratio through the gears and 10 pinions 5, 6, 8, and 9. This may be called the first reduced speed. In this case, however, though the gears 10 and 12 in the drums B and C gear with the center pinions 11 and 13, yet these central pinions can 15 rotate freely, and therefore they have no effect upon the said ratio of speed changing. When the said sliding piece 21, however, is separated from the rod 14 and brought to bear upon the rod 15' the drum A is accordingly 20 released and the drum B tightened or braked, so that the motion of the shaft 1 is transmitted to the pinion 11 through the pinion 5 and gears 6 and 10. In this case, the shaft 7 will not remain stationary 25 but will rotate around in the direction shown by the arrow X in Fig. 2. The speed of the rotation of the shaft 7 in that direction, however, is effected by the central pinion 11 which is fixed and the corresponding planet 30 gears 10 which revolve around the pinion 11. Thus in this example, the speed of the gears 10 will be reduced by the speed of the shaft 7. The shaft 2 must be rotated at the second 35 reduced speed. In this case the central pinion 13 in the drum C will rotate freely and have no effect upon the reducing of the speed. 40

Again similarly, when the drums A and B are freed or released and the drum C is braked, the third reduced speed may be obtained on the same reason as in the former case wherein the drum B is fixed. In this case, however, the central pinion 11 in the drum B will rotate freely and have no effect 45 upon the reducing of the speed.

As above described, in this example, three kinds of reduced speeds can be obtained by stopping or braking one of the three drums at a time. The rate of the said speed reducing can be varied by suitably choosing the pitch circle of the respective pinions and gears. For instance, the first reduced speed may be one half, the second one fourth of the motor speed, and especially the third 55 may give the car a reversing travel. Moreover, as far as the number of the drums and gears are concerned they may be increased for the purpose of obtaining additional and various speeds.

60 Two of the salient features of this invention are the construction of these four sets of gears in one casing, and the means for obtaining the first reduced speed when the shaft 2 is geared with the shaft 1 without using the previously employed clutch. 70

The change speed gear above described is arranged in one casing 4. This casing 4 is supplied with oil by opening a plug 4', so that the said gears are dipped into oil bath in order to smoothly rotate therein. At the same time, the splash of oil owing to the rotation of the drums will insure of the oil being deposited in an oil pocket 45, from which it flows through passage 46 into chamber 47 and returns back to the casing 4 through a hole 48. 1' represents a fly wheel fixed to the shaft 1.

The said sliding arm 23 is fixed to a shaft 24.

This shaft 24 may be slid by means of a hand shifting lever or handle (not shown) projecting on the side of the driver's seat or at any other suitable position within convenient reach of the driver, and permits the arm 23 being brought to the desired position. The end of the arm 23 is engaged with the sliding piece 21, and by the movement of the arm 23, the piece 21 may be slid on a squared shaft 22 without any rotation. The shaft 22 is rotatably supported 95 on a bearing 22' which is provided on one side of the casing 4, and is furnished with a double-armed lever 24' at the outer end. At the end of the short arm of lever 24', there is pivoted a rod 26, which is arranged in a 100 tube 27. A coil spring 25 is arranged about the rod 26 and this spring is strongly compressed in the tube 27 while its tension may be easily adjusted. Thus the left end of the spring 25, in Fig. 3 bears against the left 105 end of the tube 27, while the right end thereof bears against a stopper 25' fixed to the rod 26 by means of a nut 26'. Therefore the rod 26 is acted upon by the spring so as to be always attracted from left to 110 right in Fig. 3. Therefore the lever 24' and the rod 22 fixed thereto have always a tendency to rock, in the direction of the arrow Y, on the bearing 22' of the rod 22, and thus the said sliding piece 21 on the rod 22 acts 115 as follows: The sliding piece 21 compresses one of the coiled springs encircling the rod 14', 15' or 16', for instance spring 18 encircling the rod 14', in a direction from left to right in Fig. 2, and the rod 14' slides on its bearings 19 and 20 and strongly compresses the right end of the brake band 14 toward the left by means of a collar 17 fixed to the rod 14'. The brake band therefore frictionally engages the drum A and prevents rotation thereof. As already stated, even when by suitable operation of the sliding arm 23, the sliding piece 21 is brought to a position midway the rods 14' and 15', or 15' and 16', the spring 25 will act in the 120 125 130

manner described so as not to interfere with the sliding of piece 21 and neither are the brake bands affected while all of the drums may be freely rotated so that power will not be transmitted from the shaft 1 to the shaft 2. Though the displacement of the sliding piece 21 from one position to another, is caused by the operation of the sliding arm 23 as before mentioned, it is to be understood the rod 22 must first be rotated in a direction opposite to the direction indicated by the arrow Y or against the action of the spring 25, and thus separates the sliding piece 21 from either of the rods 14', 15' or 16', so that the end of the sliding piece will not interfere with the said rods. For this purpose, to the end of the long arm of the lever 24' a link 28 is pivoted, and to the other end of this link one end of a crank lever 29 is pivoted. This crank lever 29 is pivoted at point 30 on a bracket made in one piece or fixed to the casing 4. The other end of the crank lever is, through levers 31, 32 and 33 connected to a working lever 34 pivoted to the shaft 35. Therefore when the upper end of the lever 34 is pulled by the foot or hand of the driver, the lever 34 will rock around the shaft 35 and accordingly pull upward by the arm of lever 29 which is connected to 31. This motion is transmitted to the lever 24 which together with the shaft 22 is rocked against the action of the spring 25, on the bearing 22' of the shaft. Thus, the sliding piece 21 is rocked as desired in a direction opposite to the direction indicated by the arrow Y and the sliding arm 23 may be brought to a desired position on the shaft 22. Further in this invention, the working lever 34 may also be used to operate the brake apparatus which stops the rotation of shaft 2. This apparatus comprises a double armed lever 42-43 pivoted on the shaft 30, the shaft arm 43 of which is provided with a projection 44. The end of the long arm 42 is pivoted to one end of a link 41, and the other end of the link 41 is pivoted to one end of a lever 39, while in turn the other end of the lever 39 is pivoted to a rod 38. This rod 38 is the working rod for the brake band 37 which is intended to stop the brake drum D. The upper end of the brake bands 37' are suspended at the point 36 on the casing and the lever ends 37' are engaged by the said rod 38. A coiled spring 38' encircles the rod 38 and is arranged between the ends 37' of the brake band sections. To the extremity of the brake band at left in Fig. 3 one end of a rod 40 is connected while the outer end of the rod 40 is in turn connected middle position of the rod 39 as shown at 40'. Therefore, until the working lever 34 is operated beyond a certain amount, the lever 29 will not come into contact with the projection 44 of the arm 43, and the stop apparatus will have no action, but when the lever 29 is moved beyond the said amount it comes into contact with the projection 44 the double arm lever 43-42 is rocked upwardly about the shaft 30. This in turn causes the rod 39 to rock about the point 40' and in consequence cause a tightening of the brake band on the drum D against the tension of the spring 38' while at the same time, any of the speed change gear which may be working are automatically separated from the motor shaft 1.

Claims:

1. In a variable speed gearing apparatus for motor cars, the combination with the driving and driven shafts, of a casing surrounding the meeting ends of the shafts, drums loose on the shafts, variable planetary gearings mounted in the drums and on the shafts, brake bands encircling the drums, a slidably and rotatably mounted member designed to act in conjunction with any one of these bands, spring tensioned means associated with the member for causing an application of any one of the brake bands, a brake drum on the driven shaft, a brake band surrounding the brake drum, and a lever mechanism designed to be moved a predetermined extent for acting against the spring tensioned means to permit of an adjustment of the slideable member and to actuate the last mentioned brake band when moved beyond such predetermined extent. 95
2. An apparatus as claimed in claim 1, wherein the spring tensioned means consists of a tube carried by the casing, a slideable rod in the tube having one end pivotally connected with a part of the lever mechanism, a stopper adjustably connected to the opposite end of the rod and a coil spring arranged about the rod and within the tube having its ends bearing against the stopper and the inner end of the tube. 100
3. An apparatus as claimed in claim 1, wherein a rod square in cross section is rotatably mounted on the casing and designed to receive the slideable and rotatable member. 110
4. An apparatus as claimed in claim 1, wherein the lever mechanism includes a lever carried medially of its end on the element which supports the slideable and rotatable member and has one portion connected with the spring tensioned means, a bell crank lever pivoted on the casing, a link between one portion of the bell crank lever and the opposite portion of the first mentioned lever, a swingably mounted manually operable lever, and a connection between the swingably mounted lever and the other portion 120 of the bell crank lever. 115
5. An apparatus as claimed in claim 1, wherein that portion of the lever mechanism which actuates the brakes after the mechanism has been moved a predetermined 130

extent consists of a rod slidably arranged between the ends of the band on the first drum, an arm connected to one end of said band, a lever pivoted to one end of the arm and having one end pivotally connected to the rod, a link pivotally connected to the opposite end of the lever, a pivotally mounted bell crank lever having one portion connected to the opposite end of the link, and a 10 stud on the opposite portion of the bell crank lever and designed to be engaged by another part of the mechanism to insure of a

swinging of the bell crank lever and a consequent application of the band on the brake drum.

In testimony whereof we have hereunto set our hands in presence of two subscribing witnesses.
